GEORGE R. W. ROBERTS AND HARRY HOOPES SEELY, OF ALAMEDA, CALIFORNIA.

FLUID-ACTUATED ALARM.

1,083,299.

Specification of Letters Patent.

Patented Jan. 6, 1914.

Application filed February 18, 1913. Serial No. 749,106.

To all whom it may concern:

Be it known that we, GEORGE R. W. ROBERTS and HARRY HOOPES SEELY, citizens of the United States, residing at Alameda, in the county of Alameda and State of California, have invented certain new and useful Improvements in Fluid-Actuated Alarms, of which the following is a specification.

Our invention relates to that class of fluid-actuated alarms in which the delivery of the fluid, both as to time and duration, is under the immediate control of the operator, thereby adapting them for use on street railway cars and electric trains.

Our present invention more particularly relates to that fluid-actuated gong for which we have been granted Letters Patent No. 1,047,706, dated December 17, 1912. In that device the actuating fluid is delivered through a single nozzle and is controlled by a single valve which is, in its best form, operated by a foot-pedal. This results in a more or less leisurely initiation of the alarm and its uniform continuance.

The object of our present invention is to provide for a quick and peremptory start, and a subsequent continuance of gentler quality. The continuance may be either uniform, or varied in intensity to produce a pulsating alarm, with rising and falling inflection, thereby adding to the effect and value of the notice given.

A further object of our invention is to economize the fluid necessary to operate the alarm.

To these ends our invention consists in the novel fluid-actuated alarm and the novel construction of its controls, which we shall now fully describe by reference to the accompanying drawings, in which—

Figure 1 is a front elevation of our device, broken and partly in section. Fig. 2 is a side view of the same in elevation.

1 is a portion of the supporting structure, which may be considered as the platform of a car.

2 is a bracket bolted to the platform, said bracket carrying the device.

The sound producing portion of the device may be of any suitable nature. For illustration we here show it as comprising a gong 3, a striker 4, a shaft 5 carrying the striker, and an impact wheel 6 on the shaft.

7 is the primary fluid conduit, which at one terminal communicates with the primary nozzle 8, the tip of which is in proper

relation to the impact wheel 6 to drive said wheel by the impingement thereon of the delivered fluid; and at its other terminal said primary conduit communicates with the inlet chamber 9, with which the inlet pipe 10 from the fluid-source communicates. The communication between the inlet chamber 9 and the primary conduit 7 is controlled by a valve 11 within said chamber, said valve being normally held to its seat by a spring 12. The valve 11 has an uprising stem 13, the top of which is best provided with a cap 14, said cap being in contact with the lower end of a stem 15 of a foot pedal 16 mounted in the car platform 1.

The communication of the primary conduit 7 with the primary nozzle 8 is controlled by an automatic pressure valve 17, the stem 18 of which is carried by a piston 19, slideable in a cylinder 20. The piston is exposed at its front end to the primary conduit 7 and is held forward, to keep the valve 17 normally closed, by a spring 21. In the upper wall of the cylinder is made a passage 22 which leads from the primary conduit 7 in advance of the valve 17 back into a chamber 23 in the rear end of the cylinder. The inner end of the piston 19 is exposed to said chamber. In the lower wall of the cylinder is made a passage 24 which leads from the cylinder bore in the path of movement of the piston, forward to and communicates with the secondary nozzle 25, also adapted to deliver the fluid upon the impact wheel 6. It will be seen that the passage 22, chamber 23 and passage 24 form a secondary fluid-conduit from the primary conduit to the secondary nozzle 25.

The operation is as follows: When the pedal 16 is pressed and held down, the valve 11 is opened, and the actuating fluid passes into the primary conduit 7 with full volume and pressure. The immediate effect of this pressure, acting upon the exposed forward end of the piston 19 is to force said piston back, thereby withdrawing the valve 17 from its seat and opening the communication to the primary nozzle 8. With this full volume of fluid the impact wheel is given a quick start resulting in a peremptory initial warning produced by the striker 4 on the gong 3. It will be noted that this backward movement of the piston 19 causes said piston to cover and close the lower passage 24 opening from the cylinder bore to the secondary nozzle 25. A part of the

2

fluid from the main conduit 7 flowing through the upper passage 22 of the cylinder passes into the cylinder chamber 23 and as soon as the pressure in this chamber accumulates to a point where the pressure in front and behind the piston 19 is equal, the spring 21 will move said piston forward with the result of closing the valve 17 on its seat. This cuts off the fluid pressure through the primary nozzle 8, and thereupon, the piston by its forward movement having opened the lower passage 24, the fluid will flow from the primary conduit 7, through the secondary conduit formed by the upper passage 22, cylinder chamber 23, the lower passage 24, to the secondary nozzle 25, and thereafter the alarm will be operated by this nozzle. This last operation may be uniformly continuous and of gentler quality, or, if desired, the operator may by successive foot pressures and releases on the pedal 16 cause a rapid succession of the whole operation both primary and secondary, thereby producing a pulsating alarm with increased and diminished cadence. When the operator finally releases the pedal, the parts return to normal quiescence. It will readily be seen that by this arrangement, there may be great saving in the amount of fluid necessary to operate the alarm.

We claim:—

1. In a fluid-actuated alarm, the combination of an alarm device operated by fluid pressure; a primary fluid connection to operate said alarm device; a valve for controlling said primary fluid connection at the will of the operator; a secondary fluid connection to operate said alarm device, said secondary fluid connection communicating with the primary fluid connection at a point between the valve and the outlet of said latter connection; and pressure-operated means disposed to simultaneously close the secondary connection and open the primary connection and vice versa.

2. In a fluid-actuated alarm, the combination of an alarm device operated by fluid pressure; a primary fluid-nozzle and a primary fluid-connection serving said nozzle to initiate the operation of said alarm device; a valve for controlling said primary connection; means under the control of the operator for operating said valve; a secondary fluid-nozzle and a secondary fluid connection serving said nozzle and communicating with the primary fluid-connection between its nozzle and valve for continuing

the operation of said alarm device; and pressure-operated means disposed to simultaneously close the secondary connection and open the primary connection and vice versa.

3. In a fluid-actuated alarm, the combination of an alarm device operated by fluid pressure; a primary fluid-connection to initiate the operation of said alarm device; a valve for controlling said primary connection; means under the control of the operator for operating said valve; a secondary fluid-connection communicating with the primary connection between its valve and outlet for continuing the operation of said alarm device; a second valve controlling the primary connection beyond the communication of the two fluid connections; and a spring controlled piston carrying said second valve, exposed at opposite ends to the primary and secondary fluid-connections, said piston being disposed to simultaneously close the secondary connection and open the second valve of the primary connection, and vice versa.

4. In a fluid-actuated alarm, the combination of an alarm device operated by fluid pressure; a primary fluid-nozzle to initiate the operation of said alarm device; a primary fluid-connection from a fluid source to said primary nozzle; a valve under the control of the operator to control the admission of the fluid to said primary connection; a secondary fluid-nozzle to continue the operation of said alarm device; a secondary fluid-connection communicating with the primary fluid-connection between its nozzle and valve and with the secondary fluid-nozzle; a second valve controlling the communication of the primary fluid-connection with the primary fluid-nozzle at a point beyond the communication of the two connections; and a spring-controlled piston carrying said second valve and exposed at opposite ends to the pressure in the two fluid connections, said piston being disposed to simultaneously close the secondary connection and open the second valve of the primary connection, and vice versa.

In testimony whereof we have signed our names to this specification in the presence of two subscribing witnesses.

GEORGE R. W. ROBERTS.
HARRY HOOPES SEELY.
